Int. Cl. D8—03

U.S. Cl. D8—125

The figure is a perspective view of a handbag frame, showing my new design, where the side opposite that disclosed is the same.

The characteristic feature of my design resides in the combination on a handbag frame of spaced apart perforations and intermediate similar bosses in groups of five, all as shown on the drawing.

I claim:

The ornamental design for a handbag frame, substantially as shown and described.
